COLLAPSIBLE ROCKING CHAIR

George C. Herschell, Portland, Oreg.

Application December 10, 1956, Serial No. 44,141

Term of patent 14 years

(Cl. D15—6)

Fig. 2.

Fig. 1.

Figure 1 is a perspective view of the front of a collapsible rocking chair, and showing my new design; and Figure 2 is a rear perspective view thereof.

I claim:

The ornamental design for a collapsible rocking chair, as shown.
